CONTROL FOR WATER SOFTENING APPARATUS

Lynn G. Lindsay, St. Paul, Minn.

Application October 2, 1948, Serial No. 52,551

3 Claims. (Cl. 210—24)

1

This invention relates to water softening apparatus and controls therefor, and particularly to controls for water softeners of the type wherein the water is caused to flow through a porous body of the water softening material which requires regeneration periodically.

It is an object of my invention to provide for apparatus of this class an improved, semi-automatic control and timing mechanism which requires a minimum of skill and effort on the part of the operator and whereby the periodic regeneration of the softening material is facilitated.

A particular object is to provide in a control of the class described peculiarly inexpensive and reliable means for accurately limiting and restricting the rate of flow of regenerating liquid through the softening material during regeneration, in combination with means for rapidly drawing off the water which must be displaced to permit the charging of the apparatus with regenerating material.

Another object is to provide in association with a valve member which is spring biased to one position and adapted to be manually set in another position, novel and improved latch mechanism adapted to be actuated by clock mechanism to cause the valve member to move to the first mentioned position after the elapse of a predetermined period of time.

Further objects are to provide an inexpensive, compact and efficient control which is particularly, although not exclusively, adapted to facilitate the regeneration and flushing of domestic water softeners.

The invention also includes certain other novel features of construction which will appear and be more fully pointed out in the following specification and claims.

Referring to the accompanying drawings which illustrate, by way of example and not for the purpose of limitation, a preferred embodiment of my invention:

Figure 1 is a side elevational view showing my improved control on a water softener of the up-flow type, the softener being shown in central vertical section;

Fig. 2 is a top plan view of the control and showing the water softening apparatus in horizontal section, the section being taken approximately on the line 2—2 of Fig. 1;

Fig. 3 is a horizontal section through the softener tank taken on the line 3—3 of Fig. 1;

Fig. 4 is a central, longitudinal section through the hard water inlet fitting;

2

Fig. 5 is a fragmentary, central vertical section through the timing control valve, with the movable valve members in regenerating and flushing position;

5 Fig. 6 is a fragmentary vertical section taken approximately on the line 6—6 of Fig. 5;

Figs. 7 and 8 are elevational views showing the coacting cam disks for actuating the valve latch mechanism;

10 Fig. 9 is a side elevational view showing the timing control valve;

Fig. 10 is a rear elevational view of the same with a portion of the latch casing broken away;

15 Fig. 11 is a central vertical section through the timing control valve with the movable members in water softening position;

Figs. 12 and 13 are cross sectional views, taken approximately on the lines 12—12 and 13—13 respectively of Fig. 11, and

20 Fig. 14 is an end view of the drain restricting valve head.

The water softening apparatus illustrated in the drawings has a substantially cylindrical tank 15 containing a body 16 of water softening material supported on a bed 17 of gravel. The tank has a top opening and a removable cap 18 which allows access to a brine compartment 20 in the upper portion of the tank for purposes of charging with granular regenerating material and for cleaning. A horizontally extending partition 19 separates the lower portion of the tank from the brine compartment 20. Hard water is admitted to the chamber 20 through a pipe 21 under control of a valve 22 and the water enters the tank through a fitting 23 (Figs. 1, 2 and 4) having a restricted inlet port 24 adapted to direct the water at high velocity in a swirling manner into the chamber 20, the fitting 23 being disposed off center to direct the water substantially tangentially to the cylindrical wall of the chamber 20.

An axially extending pipe 25 is rigidly connected at its upper end to the partition 19 and extends downwardly and centrally therefrom to a point near the bottom of the tank. Water is admitted to the upper end of the pipe 25 through a strainer tube 26 which fits loosely in the upper end of the pipe 25 and is supported by a cotter key 27 extending through a perforation in the tube and resting on the upper surface of the partition 19. To facilitate cleaning of the strainer tube 26 it is thus made readily removable through the opening in the top of the tank when the cap 18 is open.

Fixed on the lower end of the pipe 25 is a horizontally extending baffle plate 28 having integral

members 28 projecting downward to rest on the inner surface of the tank bottom.

An outlet for the tank 15 is located at an elevation above the water softening material 16 and is provided with a strainer tube 30 which extends horizontally within the tank and communicates with the inlet port of my improved control valve having a casing indicated generally by the numeral 31. The tank outlet fitting comprises a threaded nipple 32 in which an inlet port 33 for the casing 31 is formed. This main control valve casing is also formed with a drain port 34 communicating with the waste or drain pipe 35 and a service port 36 communicating with a service pipe 37 adapted to conduct soft water to the faucets or other service outlets.

As best shown in Fig. 12 the drain port 34 is in continuous communication through a passage 38 with a chamber 39 formed in the casing 31. Movable in the chamber 39 is the head 40 of a valve member adapted to limit and control the rate of flow of liquid from the softener to the drain pipe. This valve head 40 has a conical face adapted to close against a seat 41 formed in the casing 31 and extending across the face of the conical surface is a kerf 42 (Fig. 14) adapted to permit continuous flow of water at a predetermined fixed rate when the head 40 is in closed position against its seat 41. The head 40 is mounted on a screw threaded stem 43 which projects to the interior of the casing and is operative by means of a handle 44 to move the head 40 to and from the seat 41.

Spaced annular valve seats 45 and 46 are provided in the casing 31 for a valve head 47 which is fixed on an operating stem 48 and adapted to be moved from closed position in contact with one of these seats to a closed position in contact with the other seat. The port 33 opens into a chamber 49 extending between the valve seats 45 and 46 and a chamber 50, also formed in the casing 31, is connected by a passage 51 to allow flow of liquid to the seat 41 and valve head 40 which controls the rate of flow to the drain passage 38 and the drain pipe 35. Thus when the head 47 is closed against its seat 45 flow of liquid from the inlet port 33 to the service port 36 and pipe 37 is permitted and flow from the port 33 to chamber 50 is cut off. When the head 47 is closed against its seat 46, flow to the service pipe 37 is substantially cut off and flow to the drain pipe 35 is permitted at a rate which is determined either by the fixed orifice defined by the kerf 42 or by the enlarged passage between the head 40 and seat 41 when the head is in open position. The valve head 47 is spring biased toward closed position on its seat 45 by a spring 52 which is confined on the stem 48 between a head 53 fixed on the outer end thereof and a bearing 54 formed in the casing 31.

Mounted in axial alignment with the valve stem 48 is a plunger 55 having an operating knob 56 on its outer end and carrying a spring 57 in a recess in its inner end. The spring 57 normally projects to engage the outer face of the head 53 and to transmit thrust to the stem 48. An annular shoulder 58 is formed on the plunger 55 for engagement with latch mechanism comprising a radially movable detent 59 mounted in a housing 60 carried by the outer end portion of the valve casing 31. The casing 60 is formed with a cylindrical bearing member 60a which embraces the casing 31 and is secured thereto by means of set screws 60b (Fig. 9). A pair of anti-friction rollers 61 are carried by the lower end

of the detent 59 for rolling engagement with the shoulder 58 on the plunger 55 and with radially extending guide surfaces formed in the housing 50. A guideway 59a is formed in the housing 60 to slidably receive the detent 59.

As shown in Fig. 11, the detent 59 is spring biased outward from the plunger 55 by a spring 62 which is connected at its lower end to the detent and anchored at its upper end to a pin 63 projecting from the housing 60. Carried by the upper end portion of the detent 59 is a small roller 64 (Figs. 6 and 11) which is held in rolling contact with the peripheries of cam disks 65 and 66, shown separately in Figs. 7 and 8. These disks are mounted in face to face contact one with the other on a spindle 67 which projects from the front of the housing 60 and has a manually operable knob 68 fixed on its front end for manual operation of the spindle. The cam 66 is fixed on the spindle 67 and the cam 65 is free to turn thereon within the limits determined by the movement of a pin 69, which projects from the cam disk 66, in an arcuate slot 70 formed in the disk 65. A recess 71 is formed in the otherwise circular periphery of the cam disk 65 and a recess 72 of somewhat different shape is formed in the otherwise circular periphery of the cam disk 66, both of these recesses being adapted to receive the roller 64 carried by the detent 59. A cam surface 72a extends at a gradual incline from the inner extremity of the recess 72 to the outer periphery of the cam disk 66 for engagement with the roller 64 and to actuate the latter radially outward relative to the cam disks and spindle 67 when it is desired to set the detent 59 in engagement with the shoulder 58 of the plunger 55.

The clock mechanism in the housing 60 includes a main spring 73 operatively connected to spindle 67 for winding and having a friction clutch device 74 which connects the spring 73 to the spindle 67 through suitable speed reducing gearing to turn the knob 68 counter-clockwise toward a stop pin 75 at a predetermined relatively slow rate. The knob 68 is formed with a pointer which by reference to a dial and legends on the front face of the housing 60 may be set for a suitable period of time corresponding to the time required for regeneration and flushing of the body of softening material 16.

As shown in Fig. 13, the seat 43 for the valve head 47 is formed with a minute kerf 76 which permits equalization of the pressure at opposite faces of the head 47 when the latter is closed against its seat 46. I thereby guard against the holding of the head 47 in closed position on the seat 46 with sufficient fluid pressure to prevent the expansion of spring 52 when the valve stem 48 is released by withdrawal of the detent 59 from engagement with the shoulder 58 at the end of the regenerating and flushing period.

Operation

During the normal water softening operation the valve head 40 is closed against its seat 41, the head 47 is closed against its seat 45, as indicated in Figs. 12 and 11 respectively, and the valve 22 is open. This allows hard water to pass from the pipe 21 into the chamber 20, from this chamber through the slots in the strainer tube 26, downward through the pipe 25 and to flow from the outer perimeter of the baffle plate 23 into and

through the bodies of gravel 17 and water softening material 16. The hardening salts are thereby removed from the water and the soft water is forced out of the tank through the strainer tube 30 into the valve casing 31 through the port 33 and out the service port 36 and pipe 37 past the valve seat 46.

When regeneration is required, the valve 22 is closed to cut off the supply of hard water to the tank 15 and the valve handle 44 is turned to withdraw the head 40 from the seat 41. The cap 18 is then removed, allowing air to enter chamber 20, and a sufficient quantity of water is allowed to flow out of the chamber 20 through pipe 25 and valve casing 31 for replacement by the charge of common salt or other regenerating material which is to be placed in the chamber 20 through the top opening. By providing for the quick and wide opening of the valve head 40 relative to its seat 41 thereby allowing water to flow rapidly from the salt chamber 20 to the drain pipe 35 under the small head of gravity available, I greatly facilitate and hasten the initiation of the generating treatment. This is particularly advantageous with water softening apparatus of the upflow type where there is only a small head of water above the drain outlet and it is necessary to provide greatly restricted flow to drain during the regenerating and flushing period.

The valve head 40 is allowed to remain in its open position for the brief period required to drain off the excess water from the tank 15 and then the handle 44 is manipulated to close the head 40 against its seat 41, regenerating material is charged into the chamber 20 and the cap 18 is closed and secured in sealed relation to the tank. As the next operation preparatory to regeneration, the knob 56 of the plunger 55 is thrust inward against the bias of the springs 52 and 57 to close the valve head 47 against its seat 46 and the knob 68 of the timing mechanism is turned clockwise to a position where its pointer indicates time in minutes required for regenerating and flushing. When the knob 68 is in its terminal position in contact with the stop pin 75, the roller 64 is in its elevated position within the recesses 71 and 72 in the cam disks 65 and 66. The operator by turning the knob 68 clockwise from its zero position causes the cam surface 72a to engage the roller 64 and to actuate this roller together with the detent 59 downward out of the recesses 71 and 72. Such movement of the knob 68 and spindle 67 brings the roller 64 in contact with the circular peripheral surfaces of the cam disks 65 and 66 so that the detent 59 is held in its downwardly extended or locking position with respect to the shoulder 58 on the plunger 55. Rotation of the knob 68 and spindle 67 in a clockwise direction also winds the main spring 73 of the clock mechanism so that thereafter, through the friction drive, the clock mechanism slowly returns the spindle 67 and knob in a counter-clockwise direction toward its initial or zero position. During this operation the circular peripheries of the cam disks 65 and 66 revolve in contact with the anti-friction roller 64. Ordinarily the time required for regeneration and flushing does not exceed one hour and my time control mechanism is preferably provided with a dial having legends and calibrated to indicate by reference to the pointer on the knob 68 suitable regenerating and flushing periods.

The operator, having set the knob 68, by reference to the dial, for the time required for regeneration and flushing, finally opens the valve 22

to start the regenerating and flushing cycle. During this cycle water at high velocity is injected into the brine chamber 20 through the nozzle port 24 which causes the water to swirl at fairly high velocity around the walls and within the chamber 20 to thereby rapidly dissolve the salt or other solid regenerating material. The resulting brine flows through the slots in the strainer tube 26, downward through this tube and pipe 25 to the bottom of the tank and thence radially outward beneath the baffle plate 28 which efficiently distributes the liquid through the gravel bed 17 and thence to the body of softening material 16. The brine regenerates the material 16 and the spent brine and impurities flow out through the strainer tube 30, valve casing 31 and drain pipe 35. Specifically, the valve head 47 being closed against its seat 46, the spent brine and impurities from the softening material enter the casing 31 through the port 33 and flow to and through the chamber 50 and passage 51 to the valve head 40, thence through the restricted passage defined by the kerf 42 to the chamber 39 and then through passage 38 and port 34 to pipe 35. The rate of flow to the drain is thus determined by the cross sectional area of the kerf 42 in the valve head 40 and pressure of the water. For best results the rate of flow must be regulated in accordance with the hardness of the water and available pressure.

The valve members remain in the regenerating position for a period of time somewhat in excess of that required for regenerating in order to allow time for the flushing operation or washing out of the brine and impurities. The brine is displaced by clear water which flows upward through the material 16 and out through the casing 31 to the drain 35, as described. When this flushing has continued for the required period of time the timing mechanism automatically returns the apparatus to normal softening operation. The required reversal of the position of the valve head 47 takes place when the recesses 71 and 72 in the cam disks 65 and 66 reach a position in alignment with the roller 64 so that the roller enters these recesses under the force exerted by the spring 62 as it withdraws the detent 59 from engagement with the shoulder 58 on the plunger 55. The plunger is thereby released to the position shown in Fig. 11 and spring 52 is allowed to expand and to actuate the valve head 47 to open position relative to its seat 46 and to closed position against its seat 45, thereby stopping the flow of liquid to drain and allowing the soft water to enter the service pipe 37. The spring 57 is somewhat stiffer than the spring 52 and is only slightly compressed when the valve head 47 closes against the seat 46. The spring 57 thus compensates for wear on the valve head 47 and insures firm closing of the head against the seat 46.

By providing interchangeable valve heads 40 formed with kerfs 42 of various different and suitable cross sectional areas, my apparatus is adapted to efficiently regenerate softeners where the water to be softened is supplied at various pressures or pressure ranges and contains varying amounts of hardening salts. Since the passage defined by the kerf 42 should for most domestic installations have a cross sectional area smaller than .01 square inch, the initiation of the regenerating operation would be greatly delayed if the flow of water from the tank preparatory to regeneration were limited by the rate of flow required during regeneration. By provid-

ing the quickly movable valve head 40 I facilitate the rapid drawing off of water from the brine chamber 20 when the charge of granular regenerating material is to be charged into the tank.

A further important feature of my invention resides in the arrangement of the clock operated spindle 67 in laterally spaced relation to the plunger 55 and the latch mechanism comprising the detent 59 which is movable perpendicularly to the axes of the spindle 67 and plunger 55 in a straight line extending between said axes.

This arrangement of latch and operating mechanism is peculiarly compact and simple and results in unusually reliable operation which is further promoted by the anti-friction rollers 61 and 64 and my arrangement whereby the roller 64 throughout the time control period engages the circular peripheries of the cam disks 65 and 66 which are concentric with the operating spindle 67. With this arrangement there is a minimum of resistance to the operation of the clock mechanism and no increase or other variation in such resistance during any part of the cycle of operation.

Having described my invention, what I claim as new and desire to protect by Letters Patent is:

1. For water softening apparatus having a tank containing softening material, said tank having an outlet for liquid, a control comprising, a casing having an inlet port connected to said tank outlet, a service port connected to a service pipe and a drain port connected to a drain pipe, a valve member movable in said casing to selectively control the flow of liquid to said service or drain ports, a second valve member movable to restrict the flow of liquid to said drain pipe, a seat for said second valve member, a passage of fixed cross sectional area disposed to permit flow of liquid at a predetermined rate past said seat to the drain pipe when said second valve member is in closed position relative to said seat and means for actuating said second valve member to an open position relative to said seat to thereby increase the rate of flow to said drain pipe.

2. For water softening apparatus having a tank containing softening material, said tank having an outlet for liquid, a control comprising, a casing having an inlet port connected to said tank outlet, a service port connected to a service

pipe and a drain port connected to a drain pipe, a valve member movable in said casing to selectively control the flow of liquid to said service or drain ports, a second valve member movable in said casing to restrict the flow of liquid to said drain port, said casing being formed with a seat for said second valve member, a passage of fixed cross sectional area disposed to permit flow of liquid at a predetermined rate past said seat to the drain pipe when said second valve member is in closed position relative to said seat and means for actuating said second valve member to an open position relative to said seat to thereby increase the rate of flow to said drain pipe.

3. For water softening apparatus having a tank containing softening material, said tank having an outlet for liquid communicating with said tank at an elevation above the water softening material therein, a control comprising, a casing having an inlet port connected to said tank outlet, a service port connected to a service pipe and a drain port connected to a drain pipe, a valve member movable in said casing to selectively control the flow of liquid to said service or drain ports, a second valve member movable to restrict the flow of liquid to said drain pipe, a seat for said second valve member, a passage formed in said second valve member to permit flow of liquid at a predetermined fixed rate past said seat to the drain pipe when said second valve member is in closed position relative to said seat and means for actuating said second valve member to an open position relative to said seat to thereby increase the rate of flow to said drain pipe.
